Francilla Whitney Inventor

By Lancaster and Follins
his Attorney General

UNITED STATES PATENT OFFICE.

FRANCILLA WHITNEY, OF DORCHESTER, MASSACHUSETTS.

COMFORTER.

1,349,540.

Specification of Letters Patent. Patented Aug. 10, 1920.

Application filed August 16, 1918. Serial No. 250,216.

To all whom it may concern:

Be it known that I, FRANCILLA WHITNEY, a citizen of the United States, and a resident of Dorchester, in the county of Suffolk and State of Massachusetts, have invented certain new and useful Improvements in Comforters, of which the following is a specification.

This invention relates to bed comforters or coverlets, and an object of the invention is to provide a comforter including a layer of paper between two relatively thin layers of fabric and to construct the comforter in such manner as to eliminate the inconveniences contingent with the ordinary or formerly known paper blankets or comforters.

It is well known, that paper is a heat non-conductor and when used with relatively light fabric, forms a warm comforter, which is light in weight and does not cause fatigue, to the person or persons sleeping beneath the same, by reason of its weight, however, paper prevents proper respiration of a person's body, and also when used in continuous sheet in a comforter will become worn and torn, upon excessive folding and it is an object of this invention to provide a comforter which will overcome the above objections, by providing a plurality of strips of paper which extend longitudinally of the comforter and have their facing edges spaced, from each other, to permit air passage through the cloth between the respective strips of paper and which also enables the comforter to adapt itself to the shape of the person sleeping beneath the same, allowing the said person to move without causing any considerable noise or rattling of the paper.

Other objects of the invention will appear in the following detailed description, taken in connection with the accompanying drawing, forming a part of this specification, and in which drawing:

Figure 1 is a plan of the comforter having parts broken away.

Fig. 2 is a section on the line 2—2 of Fig. 1.

Fig. 3 is a section on the line 3—3 of Fig. 1.

Referring more particularly to the drawing, 1 generically indicates the comforter which is composed of three layers, namely an upper layer 2 of fabric, an intermediate layer 3 of paper, and an under layer 4 of

fabric. The fabric layers 2 and 4 are preferably constructed of some light artistic or pretty fabric, so as to add to the attractiveness of the comforter.

The intermediate layer 3 of paper, is formed of a plurality of separate strips 5, which extend longitudinally of the comforter throughout its entire length, and have their facing edges spaced, as shown at 6, so as to permit the passage of air through the comforter to insure the proper respiration of the body of the sleeper.

The edges of the comforter are bound by a suitable binder strip or strips 7 which are folded over the edges of the layers 2, 3 and 4 and have their edges folded back upon themselves as shown at 8 in Fig. 3 of the drawing. These folded edges of the edging strip or strips 7 are stitched to the layers 2, 3 and 4 of the comforter by the ordinary type of stitching as indicated at 9. Binder strips 10 extend longitudinally of the comforter, and they have their edges bent back upon themselves as shown at 11. These binder strips 10 extend over the spaces between the various strips 5 of paper and are stitched, by stitching as indicated at 12 through the edges of the layers or strips 5 of paper and the upper and under layers 3 and 4 of fabric, forming means to securely connect the edges of the strips 5 of paper to the upper and under sheets of fabric. The binder strips 7 and 10 may be of suitable color corresponding to the colorings of the fabric strips so as to cause the entire comforter to please the esthetic sense of the user.

It is to be understood that the paper of which the strips 5 are made, is preferably to be made of tough non-crinkling paper having sufficient calender to make it non-conductive of heat.

Changes in details may be made without departing from the spirit of the invention, but;

I claim:

1. In a comforter, a succession of elongated narrow strips of paper placed transversely across the body of the comforter and having the edges thereof spaced apart, a layer of fabric placed beneath said succession of paper strips and being continuous over the entire body of the comforter, said fabric extending across the spaces left between the edges of said paper strips, a second piece of fabric placed in common over the succession of paper strips and passing

- across the spaces left between such strips, said paper strips adapted to exclude the free passage of air except at the spaces, reinforcing strips secured to the fabric and 5 paper strips and bridging the spaces between said paper strips, and a reinforcement for the edges of the comforter secured alike to the fabric and paper strips for securing the same in assembled relation.
- 10 2. A comforter composed of a succession of rectangular elongated paper strips disposed transversely of the body of the comforter and having the adjacent edges thereof spaced apart, a piece of fabric of substantially 15 the size of the comforter body placed beneath said paper strips and extending across the papers therebetween, a similar piece of flexible fabric also of substantially

the size of the body of the comforter placed above said paper strips and also extending 20 across the spaces therebetween, transversely extending fabric binder strips extending over the top piece of fabric and bridging the spaces between said paper strips, said binder strips having the edges thereof 25 turned beneath the body portions of the binder strips, lines of stitching going through said paper strips, pieces of fabric and binder strips at the doubled-over edges thereof, and a binding placed about the 30 edges of the comforter body and being secured to the paper strips and pieces of fabric.

FRANCILLA WHITNEY.

In the presence of—

HERBERT N. HANSON.
